UNITED STATES PATENT OFFICE.

CARL J. ULRICH, OF MANKATO, MINNESOTA.

MACHINE FOR WASHING SERVING TRAYS.

Application filed November 16, 1923. Serial No. 675,073.

- My present invention relates to machines for washing serving trays used in restaurants, cafeterias and the like and is of the type disclosed and claimed in a co-pending application jointly invented by myself and one W. A. Miller, filed June 13, 1921, under Serial Number 477,103, and has for its object to improve the same in the several particulars hereinafter noted.
- 10 In the accompanying drawings, which illustrate the invention, like characters indicate like parts throughout the several views. Referring to the drawings:
- Fig. 1 is a perspective view of the invention;
- Fig. 2 is a view principally in longitudinal central section;
- Fig. 3 is a view principally in transverse vertical section;
- 20 Fig. 4 is a detail view with some parts sectioned on the line 4—4 of Fig. 2, on an enlarged scale;
- Fig. 5 is a fragmentary plan view of one of the feed screws and trays;
- 25 Fig. 6 is a perspective view of the free end of one of the switch rails; and
- Fig. 7 is a detail view of one of the free ends of one of the switch rails and co-operating track rails, said track rail being shown 30 in section.
- The numeral 8 indicates a water-containing drum or receptacle mounted on a skeleton frame 9 and having at its sides bearings 10. Said receptacle 8 has flat parallel sides 35 and a curved bottom struck from a center at the axis of said bearings 10. The front wall of the receptacle 8 is on an incline and extends tangentially from the curved bottom, and the back wall of said receptacle is 40 on the same curve as said bottom and terminates substantially in a horizontal plane that extends through the axis of the bearings 10. The front wall of the receptacle extends above the rear wall thereof, and 45 the front upper edge portions of the sides of said receptacle extend horizontally rearward from the front wall thereof to a point directly above the axis of the bearings 10. The rear upper edge portions of the sides 50 of the receptacle 8 are on the same curve as the rear wall of said receptacle.
- Leading from the bottom of the receptacle 8 is a drain pipe 11 normally closed by a valve 12. An overflow pipe 13 leads from 55 the receptacle 8, at the rear thereof, empties into the drain pipe 11 outward of the valve 12, and determines the level of the water in said receptacle.
- Within the receptacle 8 is a pair of guide rails 14 that extend from the upper edge of the front wall of said receptacle to a point above the rear wall thereof. These guide rails 14 rest on the front wall of the receptacle 8, and hence have the same inclination, and their rear end portions rest on the curved bottom and rear wall of said receptacle. Also within the receptacle 8 is a pair of curved guide rails 15, the intermediate portions of which are concentric with the curved portions of the outer guide rails 14 and are radially spaced therefrom. The front ends of the guide rails 15 are inclined and extend tangentially from the curved portions of said rails. The inclined front portions of the guide rails 14 and 15 are in diverging relation, as shown in Fig. 2.
- The rear end portions of the guide rails 15 are tangentially extended to afford inclined extensions 16 that extend upward and forward over the receptacle 8 at an angle of substantially forty-five degrees and have at their extreme upper ends stop fingers 17.
- A pair of inclined switch rails 18 is intermediately pivoted at 19 to the rear upper ends of the guide rails 14, and their long or upper arms normally rest on the guide rail extensions 16 materially below the stop fingers 17. Curved rods 20, attached to the lower or short arm of the switch rails 18, work in guide holes in the guide rails 14. Coiled springs 21, encircling the rods 20, are compressed between the guide rails 14 and switch rails 18 and yieldingly hold said switch rails on the guide rail extensions 16 with freedom for lifting movement therefrom. The upper ends of the switch rails 18 are undercut at 22 to receive the guide rail extensions 16, as best shown in Figs. 6 and 7, so that the upper surfaces of said switch rails are substantially flush with the respective surfaces of the guide rail extensions 16.
- For automatically feeding trays into the receptacle, I provide means for supporting a stack of trays *y* and removing successive trays from the bottom of the stack and then release the same into the receptacle 8. This means may take various different forms and in the present commercial form of the machine I provide four feed screws 23 arranged in front and rear laterally spaced pairs. The threads 24 of the feed screws 23

2

are adapted to support a stack of trays *y*, and the upper ends of said threads are cut square and their upper surfaces beveled to afford wedge-acting points 25. These feed 5 screws 23 are secured to upright shafts 26 journaled in bearings 27 secured by nut-equipped bolts 28 to the frame 9 at the sides of the receptacle 8. The front pair of bearings 27 is made adjustable toward and from 10 the rear pair of bearings 27 by extending the respective bolts 28 through slots 28' in said frame. The purpose of this adjustment of the bearings 27 is to position the feed screws 23 for trays that may vary slightly 15 in width. The feed screws 23 have truncated conical upper end portions 29 above the threads 24 for directing the trays *y* onto said threads.

Suitable means is provided for positively 20 driving the feed screws 23, as will presently appear, and it is important to note that the feed screws 23 on one side of the machine are driven in an opposite direction from the feed screws on the other side thereof to neutralize the tendency of the trays *y* to move 25 endwise on the threads 24 under the action of the rotation of said feed screws. During the rotation of the feed screws 23 the wedge-acting ends 25 of the threads 24 enter between the rolled rims of the two lowermost 30 trays *y* and separate the lowermost tray from the stack. The threads 24, acting on the separated tray *y*, carry the same downward from the stack and then release said 35 tray into the receptacle 8. This released tray *y* drops onto the inclined guide rails 14 and slides thereon into the water *x*.

To convey the trays *y* through the water *x* and above the same into draining positions 40 on the guide rail extensions 16, I provide a reel head 30 having a short shaft 31 journaled in the bearing 10. A plurality of radial arm extensions 32, as shown three, are secured to the reel head 30, work at one 45 side of the guide rails 15, and have on their outer ends horizontal extensions 33 that extend transversely over said guide rails and radially inward therefrom. On each arm extension 32 is a pair of pins 34 that extend 50 radially outward between the two guide rails 15 and are of such length as to engage a tray *y* on the guide rails 14, and push the same through the water *x* and above the same onto the guide rail extensions 16.

55 When a tray *y* supported on one pair of the pins 34 is lifted thereby out of the water *x*, said tray is in a substantially vertical position, and under further lifting movement of said tray, the same tilts under the 60 action of gravity onto the guide rail extensions 16. As the tray *y* is pushed upward onto the guide rail extensions 16 by the respective pins 34, the upper rolled edge thereof engages the switch rails 18, lifts the 65 same from the guide rail extensions 16 and

allows the tray to pass thereunder and above the same. At the time the tray passes above the switch rails 18, the respective pins 34 move out of engagement therewith, and at the same time said switch rails are again 70 closed under the action of the springs 21. As the trays *y* are released by the respective pins 34, the same slide downward on the guide rail extensions 16 onto the switch rails 18 and are conveyed thereby onto an inclined 75 shelf 35 at the rear of the machine where they may be removed by an operator who examines, dries and stacks the trays on the table 2.

The following connections are provided 80 for driving the reel head 30 and feed screws 23:

An electric motor 36 is mounted on a shelf 37 secured to the frame 9 under the front of the receptacle 8 and has on its armature 85 shaft a grooved pulley 38 aligned with a relatively large grooved wheel 39 on the front end of a counter-shaft 40, and over which pulley 38 and wheel 39 runs a belt 41. The counter-shaft 40 is journaled in 90 bearings 42 on the frame 9 and has on its rear end a worm 43 that meshes with a worm gear 44 on the shaft 31. For driving the feed screws 23 from the shaft 31, the following connections are provided: Front and rear 95 transverse shafts 45 and 46 are journaled, respectively, in the front and rear pairs of bearings 27 and have secured thereto bevelled pinions 47 which mesh with bevelled pinions 48 on the lower ends of the shafts 26. 100 A sprocket chain 49 runs over a relatively large sprocket wheel 50 on the shaft 31 and a relatively small sprocket wheel 51 on the rear shaft 46 and positively drives the same. The front shaft 45 is driven from the rear 105 shaft 46 by a sprocket chain 52 which runs over sprocket wheels 53 on the shafts 45 and 46. The driving of the shafts 45 and 46 and the arrangement and driving of the pinions 47 and 48 is such that the feed screws 23 on opposite sides of the machine are driven in reverse directions, as previously 110 stated.

From the above description it is evident that the trays *y* are automatically removed from the bottom of a stack of trays supported on the threads 24, successively deposited into the receptacle 8, moved through the water therein onto the guide rail extensions 16 into draining positions, and from 120 thence automatically conveyed by the switch rails 18 to the shelf 35 where they may be removed by an operator. After the trays *y* are cleansed by passing through the water *x*, they are rinsed by being raised between a 125 pair of spraying nozzles 54 that extend transversely of the receptacle 8 and may be attached to any suitable water supply under pressure.

Upright stop bars 55 on the sides of the 130

receptacle 8 properly position the stack of trays *y* as they are placed on the feed screws 23, and they also hold said stack against excessive endwise movement on said feed screws.

5 It may be here stated that the trays *y* as they slide from the inclined shelf 35 will automatically form a stack and the height thereof will depend on the distance between 10 said shelf and the table *z*, or if desired, the shelf 35 may be dispensed with and the trays *y* allowed to form a stack as they are delivered directly from the inclined switch rails 18.

15 The term "tray" is herein used in a broad sense to cover plates or other objects that can be stacked.

The above described invention has, in actual commercial usage, proven highly efficient 20 for the purpose had in view.

What I claim is:

1. A tray-supporting and releasing device comprising, in combination with a con-

veyor, a plurality of revoluble upright feed screws adapted to support a stack of trays 25 on their threads and successively remove the trays from the bottom of the stack and then release the same to said conveyor, said feed screws having conical truncated upper end portions for directing the stack of trays onto 30 their threads.

2. A tray-supporting and releasing device having two pairs of revoluble upright feed screws rotated in opposite directions and adapted to support a stack of trays on their 35 threads and successively remove the trays from the bottom of the stack and then release the same, said two pairs of feed screws being arranged to support the stack of trays therebetween.

3. The structure defined in claim 2 in which one pair of feed screws is adjustable toward and from the other pair of feed screws.

In testimony whereof I affix my signature.

CARL J. ULRICH.
